UNITED STATES PATENT OFFICE.

LOUIS COURTOT, OF PARIS, FRANCE, ASSIGNOR TO AMERICAN RADIATOR COMPANY,
OF NEW YORK, N. Y., A CORPORATION OF NEW JERSEY.

BOILER.

Application filed April 23, 1923, Serial No. 683,968, and in France April 27, 1922.

My invention relates to a low-pressure boiler adapted chiefly for hot water or steam heating purposes, and designed so as to be simply and economically constructed, the 5 heating power of the boiler being considerable with respect to its small size and light weight.

The walls of the said boiler comprise a plurality of hollow vertical panels of cast 10 iron which are not in direct communication with each other, but are connected together at the top and bottom by transverse collectors. Each of the said panels has the form of a flat receptacle which is closed on all 15 sides except for two apertures or nipple openings through the inner wall thereof for connecting the same with the said collectors.

The upper collector constitutes the dome 20 of the furnace, and it has an opening there- through for the escape of the products of 25 combustion to the chimney.

The lower collector constitutes the bottom of the ash pit.

The appended drawing shows three con- 25 structional forms of boiler according to the invention.

Fig. 1 is a vertical section of the first form of construction.

Fig. 2 is a cross-section on the line A—A 30 of Fig. 1.

Fig. 3 is a horizontal section of a second form of construction.

Fig. 4 is a vertical section of the third form of construction.

Figure 5 is a top view, (the cover plate 35 being removed) parts being broken away.

In the device shown in Figs. 1 and 2, the walls of the boiler are formed of four vertical panels a^1 a^2 a^3 a^4 having the shape of 40 flat receptacles, each being cast in a single piece. In order to provide a stronger construction, the inner and outer faces of each receptacle or panel may be braced by the cast cross-pieces b . At c and d are indicated

45 two transverse collectors whereof one forms the dome of the furnace and the other the bottom of the ash-pit. The said collectors of rectangular shape are connected with the

panels a^1 a^2 a^3 a^4 by the unions e which are analogous to the members used to connect radiator elements, or by flat connecting members such as flanged connections bolted in place.

The apertures f and g are formed in the outer panel; the upper aperture serves for 50 the fuel inlet and is provided with the cover h ; the lower aperture is provided with the ash-pit door j . On the other hand, a conduit k is provided in the collector c for the discharge of smoke. The hot water inlet 55 and outlet can be disposed upon the panels or upon the collectors. Ribs or wings of greater or less height are preferably formed upon the inner and outer face of the panels in order to augment the transmission of heat. 60

In the example shown in Fig. 3, each 65 of the lateral faces of the boiler comprises two panels a^2 and two panels a^3 . The boiler shown in Fig. 4 has at the rear an additional panel a^5 which forms with the panels a^3 a 70 vertical flue which conducts the smoke from the upper aperture m to the lower aperture n which is intended to be connected with the chimney.

I claim:

75 A boiler comprising a plurality of separate, hollow panels forming the vertical walls thereof; the lower portions of said hollow panels forming the vertical wall portions of the ash-pit, an opening in the lower portion of one of said hollow panels to permit of access to said ash-pit, a hollow member engaging the upper portions of said hollow panels and constituting the top of said boiler, a hollow panel member disposed intermediate of and in engagement with the ash-pit portions of said panels below said opening and forming the transverse bottom wall of said ash-pit, and communicating connections between each of said panels and said members serving to secure the same together, substantially as specified.

85 90 95 In testimony that I claim the foregoing as my invention, I have signed my name.

LOUIS COURTOT.
